UNITED STATES PATENT OFFICE

163,605

COMBINED TURNTABLE UNIT AND LAMP

Archie A. Hoffman, Peoria, Ill.

Application January 13, 1951, Serial No. 13,792

Term of patent 7 years

(Cl. D48—20)

To all whom it may concern:

Be it known that I, Archie A. Hoffman, a citizen of the United States, residing at Peoria, county of Peoria, and State of Illinois, have invented a new, original, and ornamental Design for a Combined Turntable Unit and Lamp, of which the following is a specification, reference being had to the accompanying drawing, forming a part thereof, in which:

Figure 1 is a perspective view of a combined turntable unit and lamp, showing my new design;

Figure 2 is a side elevation;

Figure 3 is a top plan view.

I claim:

The ornamental design for a combined turntable unit and lamp, as shown.

ARCHIE A. HOFFMAN.
